STREET LIGHTING ELECTRIC LIGHT BULB

William H. Dorman, Corning, N.Y., and Norman A. Moreau, Lincoln, R.I., assignors to Corning Glass Works, Corning, N.Y.

Filed Mar. 11, 1970, Ser. No. 21,857

Term of patent 14 years

Int. Cl. D26—01

U.S. Cl. D26—8

Fig. 1

Fig. 2

Fig. 3

Fig. 4

Fig. 5

Fig. 6

FIG. 1 is a side elevational view of a street lighting electric light bulb embodying our new design.

FIG. 2 is a top plan view thereof.

FIG. 3 is a bottom plan view thereof.

FIG. 4 is an enlarged sectional view taken on line 4—4 of FIG. 2.

FIG. 5 is an enlarged sectional view taken on line 5—5 of FIG. 1.

FIG. 6 is an enlarged sectional view taken on line 6—6 of FIG. 2.

We claim:

The ornamental design for a street lighting electric light bulb, as shown.
